United States Patent Office

Des. 229,597
Patented Dec. 18, 1973

229,597

TREE HOLDER

Patrick H. Wastal, 3842 Catalina St.,
Los Alamitos, Calif. 90720

Filed May 26, 1971, Ser. No. 147,277

Term of patent 14 years

Int. Cl. D11—02

U.S. Cl. D6—105

FIG. 1

FIG. 2

FIG. 3

FIG. 4

FIG. 1 is a top plan view of a tree holder showing my new design;

FIG. 2 is a side elevational view of my tree holder along line 2—2 of FIG. 1;

FIG. 3 is a bottom view of a tree holder showing my new design along line 3—3 of FIG. 2; and,

FIG. 4 is an inverted side elevational view of my tree holder along line 4—4 of FIG. 3.

I claim:

The ornamental design for a tree holder, substantially as shown and described.
